UNITED STATES PATENT OFFICE

IGNACIO CARLOS BAROUSSE, OF ELMHURST, ILLINOIS, ASSIGNOR TO INTERNATIONAL SILVER COMPANY, OF MERIDEN, CONNECTICUT, A CORPORATION OF NEW JERSEY

DESIGN FOR A SPOON OR SIMILAR ARTICLE

Application filed November 8, 1929. Serial No. 33,381. Term of patent 7 years.

To all whom it may concern:

Be it known that I, IGNACIO CARLOS BAROUSSE, a citizen of the Republic of Mexico, residing at Elmhurst, county of Du Page, State of Illinois, have invented a new, original, and ornamental Design for a Spoon or Similar Article, of which the following is a specification, reference being had to the accompanying drawing, forming part thereof, in which—

Fig. 1 is a front elevation of a spoon or similar article, showing my new design, and Figs. 2 and 3 respectively are cross-sectional views on lines 2—2 and 3—3 of Fig. 1.

The back is a plain or other conventional design.

I claim:

The ornamental design for a spoon or similar article substantially as shown and described.

IGNACIO CARLOS BAROUSSE.
